UNITED STATES PATENT OFFICE.

EMIL G. SAUER, OF BROOKLYN, NEW YORK, ASSIGNOR TO THE LOWELL
MANUFACTURING COMPANY, OF MASSACHUSETTS.

DESIGN FOR CARPET.

SPECIFICATION forming part of Design No. 25,192, dated February 18, 1896.
Application filed January 15, 1896. Serial No. 575,654. Term of patent 34 years.

To all whom it may concern:

Be it known that I, EMIL G. SAUER, a citizen of the United States, and a resident of Brooklyn, in the county of Kings and State of New York, have invented a new and original Design for Carpets and Borders, (being known as Pattern No. 5,222,) of which the following is a specification.

This invention comprises two parts—namely, the design A for a carpet and the design B for a border; and I do hereby declare that the drawing accompanying this specification conveys to any one a clear understanding of the same and is sufficient to enable such person to use my invention.

The design A is characterized by small closely-associated circular spots and dots between the spots.

The design B is characterized by large ornamental figures of irregular outline having their lower portions tapered and their upper portions surmounted by a cluster of leaf forms.

The border is further characterized by small closely-associated circular spots filling ²⁵ in the spaces between the lower portions of the large figures.

What I claim, and desire to secure by Letters Patent, is—

1. In a design for a carpet, the body A, substantially as shown.
2. In a design for a carpet, the border B, substantially as shown.
3. The design for a carpet comprising the body A and the border B, substantially as shown.

In testimony whereof I have signed my name to this specification in the presence of two subscribing witnesses.

EMIL G. SAUER.
